PNEUMATIC CUSHION HEEL PAD

Filed Nov. 9, 1931

FIG - 1

FIG - 2

FIG - 4

UNITED STATES PATENT OFFICE

JOHN CHARLES KELLER, OF CHICAGO, ILLINOIS, ASSIGNOR TO KELLER PNEUMATIC FOOTWEAR COMPANY, OF CHICAGO, ILLINOIS

PNEUMATIC CUSHION HEEL PAD

Application filed November 8, 1931. Serial No. 573,967.

My invention relates to improvements in pneumatic shock absorbing devices, and it consists in the combinations, constructions, and arrangements herein described and claimed.

An object of my invention is to provide a pneumatic shock absorbing device having substantially the resiliency of air.

A further object of my invention is to provide a means whereby air may be confined at atmospheric pressure in a thin, flexible container for shock absorbing purposes.

A further object is to provide an extremely effective shock absorbing device adaptable to be inserted within a shoe.

A further object is to provide a pneumatic shock absorbing device whereby a layer of air may be interposed between a human heel and the heel of a shoe.

A further object is to provide a pneumatic shock absorbing device in which the full resiliency of the air may be utilized for shock absorbing purposes.

A further object is to provide means whereby air may be confined in such a manner as to prevent shocks incidental to walking from being transmitted to the user to any injurious extent.

A further object is to provide means whereby the pressure of confined air may be varied as desired.

A further object is to provide a pneumatic shock absorbing device having means whereby the air in the pad may be replaced if desired.

A further object is to provide a shock absorbing device having means whereby the air contained within the device may be varied.

Other objects and advantages will appear in the following specification, and the novel features of the invention will be particularly pointed out in the appended claims.

My invention is illustrated in the accompanying drawing, forming part of this application, in which

Figure 1 is a top plan view of a shock absorbing device embodying my invention,

Figure 2 is a sectional view taken along the line 2-2 of Figure 1,

Figure 3 is a bottom plan view of the device as shown in Figure 2, a portion thereof being shown in section for revealing the valve structure, and

Figure 4 is a side elevation of my device as applied to a shoe.

In carrying out my invention, I provide a shock absorbing member which may be any desired shape but which preferably conforms in contour to the heel portion of the inner sole of a shoe and which may be constructed of any resilient material, such as, for instance, gum rubber. The body portion 1 comprises a top portion 2 and a bottom portion 3 which may be connected together at the outer edges thereof in any suitable manner such as, for instance, by vulcanizing to provide a compartment or chamber 4 therebetween. The body portion 1 may have a thickened or enlarged wall portion 5 which provides an internally extending portion or projecting portion 6 which is integral therewith and extends within the chamber 4 as shown in Figure 3. In making the body portion 1 the half portions 2 and 3 may be formed separately and then disposed one on each side of a mould which conforms in contour to the chamber 4. The half portions 2 and 3 may then be vulcanized around the edges of the mould from the point "A" to the point "B". The portions 7 and 8 of the half portions 2 and 3 may be left unvulcanized in order that the mould may be removed after which removal the portions 7 and 8 are united together.

The thickened portion 5 is provided with a transverse opening or passageway 9 therethrough for providing communication between the compartment 4 and the exterior of the body portion 1. An L-shaped valve member 10 may be provided having a stem portion 11 and a leg portion 12. The stem portion 11 may be disposed in the passageway 9 and may be provided with an enlarged head portion 11' which seals the passageway 9 whereby communication between the compartment 4 and the exterior of the body portion will be cut off. The stem portion 11 may be disposed in and withdrawn from the passageway 9 by any suitable means such as, for instance, using the leg 12. The leg 12 may also

serve as a means for properly positioning the head portion 11' within the passageway 9. If desired, a sheet or cover portion 17 conforming in general contour to the shape of the body portion may be disposed over the half portion 2 and may be fixedly connected therewith by any desired means such as by gluing it to the body portion.

From the foregoing description of the various parts of the device, the operation thereof may be readily understood. The device when disposed in the heels of shoes provides a most resilient means for absorbing the shock which is ordinarily transmitted to the wearer while walking. The body portion may be used without the valve 10 and the passageway 9 may be sealed in any suitable manner after the desired amount of air has been placed in the chamber 4. If the L-shaped member is utilized, however, the device possesses advantages in that the air in the chamber 4 may be replenished by withdrawing the L-shaped member from the passageway 9. The chamber 4 will then be reinflated by reason of the portions 2 and 3 being curved or arched outwardly in such a manner as to tend to prevent the chamber 4 from being flattened. The valve member 10 may then be replaced in the passageway 9 for confining the air within the compartment.

It will also readily be seen that should the compartment when fully inflated contain too much air to suit the needs of the wearer all that is necessary is that the valve member 10 be removed from the body portion and the half portions 2 and 3 be moved toward each other until the amount of air in the chamber 4 suits the need of the wearer at which time the valve member is redisposed in the passageway 9 for holding the desired amount of air in the compartment and for preventing any more air from entering therein. The head portion 11' will always be firmly imbedded in the projecting portion 6 when the valve member 10 is associated with the body portion by reason of the fact that the air pressure exerted on the sides of the projecting portion 6 by the air in the chamber, together with the natural elasticity of the projecting portion will hold the walls of the passageway in pressing engagement with the head portion 11'.

It will of course be readily understood that I do not confine myself to the particular form of the pneumatic shock absorbing device shown as it is obvious that a flexible casing may be made in any desired form and sealed in any suitable manner.

I claim:

1. As an article of manufacture, a flexible pneumatic cushion heel pad for shoes comprising a gum rubber body portion having a central cavity formed by outwardly extending integral and continuous concavo-convex top and bottom walls connected together at

their outer edges to form a substantially thin flat peripheral flange.

2. As an article of manufacture, a flexible pneumatic cushion heel pad for shoes comprising a gum rubber body portion having a central cavity formed by outwardly extending integral and continuous concavo-convex top and bottom walls connected together at their outer edges to form a substantially thin flat peripheral flange, the portion of the flange at the rear of the body portion being thicker than the portion of the flange at the front of the body portion.

3. As an article of manufacture, a flexible pneumatic cushion heel pad for shoes comprising a gum rubber body portion having a central cavity formed by outwardly extending integral and continuous concavo-convex top and bottom walls connected together at their outer edges to form a substantially thin flat peripheral flange, said cushion heel pad also being provided with a cover secured to said body portion, said cover extending in front of said body portion.

4. As an article of manufacture, a flexible pneumatic cushion heel pad for shoes comprising a gum rubber body portion having a central cavity formed by outwardly extending integral and continuous concavo-convex top and bottom walls connected together at their outer edges to form a substantially thin flat peripheral flange, said cushion heel pad also being provided with a cover secured to said body portion, said cover extending in front of said body portion, and being adapted to be glued to the instep portion of the insole of a shoe.

5. As an article of manufacture, a flexible pneumatic cushion heel pad for shoes comprising a gum rubber body portion having a central cavity formed by outwardly extending integral and continuous concavo-convex top and bottom walls connected together at their outer edges to form a substantially thin flat peripheral flange, the portion of the flange at the rear of the body portion being thicker than the portion of the flange at the front of the body portion, said cushion heel pad also being provided with a cover secured to said body portion, said cover extending in front of said body portion, and being adapted to be glued to the instep portion of the in-sole of a shoe.

JOHN CHARLES KELLER.
